UNITED STATES PATENT OFFICE.

CHARLES E. GODLEY, OF DETROIT, MICHIGAN, ASSIGNOR TO EDMUNDS AND JONES CORPORATION, OF DETROIT, MICHIGAN, A CORPORATION OF NEW YORK.

SIGNAL LAMP.

Application filed September 18, 1922. Serial No. 588,795.

To all whom it may concern:

Be it known that I, CHARLES E. GODLEY, a citizen of the United States, and residing at Detroit, in the county of Wayne and State 5 of Michigan, have invented a new and Improved Signal Lamp, of which the following is a specification.

This invention relates to the type of lamps disclosed in my pending application Serial 10 Number 570,670, June 24, 1922, and the object of the present invention is to provide cheap and efficient means whereby the lenses of lamps of this character may be resiliently supported.

15 This invention consists in a resilient packing sheet of thick paper board, cork, leather, rubber or other resilient material, fitting between the edges of the lenses and a rigid backing and also fitting within the door or lens 20 ring of the lamp, the sheet being apertured so as to offer no objectionable obstruction to the light rays. It also consists in means attached to the packing sheet and extending into a notch in the periphery of a corrugated 25 circular lens to prevent the lens from turning. It further consists in the details of construction illustrated in the accompanying drawing and particularly pointed out in the claims.

In the accompanying drawing, Fig. 1, is 30 a front elevation of this improved lamp. Fig. 2 is a section on the line 2—2 of Fig. 1 on a larger scale. Fig. 3 is a rear elevation of the lamp door and the packing sheet in position therein.

35 Similar reference characters refer to like parts throughout the several views.

As described in my former application, this lamp comprises a body having a back 1 and sides 2, which sides merge into the 40 semi-cylindrical top 4 and bottom 5. The front edge of the body is bent out into the inclined flange 7 and the terminal flange 8 which constitutes the edge of the body. An opening 9 may be cut in the bottom 5 to permit light to fall on a license plate, this 45 opening being closed by the sheet 10 of celluloid.

A cylindrical shell 14 having a back 15 and a radial front flange 16 is mounted in 50 the body, and in it is mounted a reflector 17. A connector tube 18 is secured in the shell 14 and supports the two light bulbs

19 and 20, the connector tube being formed with an opening 22 to permit the introduction of contacts on the end of a conductor to carry current to the contacts 23 on the bases of these lamp bulbs. These details are fully shown in the co-pending application and are therefore here omitted.

The upper lens 25 is circular with a circular shoulder 26 on its inner side and vertical corrugations 24 (Fig. 1) on its outer side. A notch 27 is provided at any convenient point. The lower lens 28 is lunate and preferably domed and its upper edge 29 fits the lens 25. The lens ring or door has a circular upper portion 31 to receive the upper lens and a circular lower portion 32 which extends around the lower lens, these two portions being connected by the straight portions 33.

The central transverse portion 34 of the door is substantially semi-circular in cross section, as shown in Fig. 2, while in the outer edge portions the transverse curvature is continued until the rear edge 35 of the door which contacts with the edge 8 of the body is within the greatest dimensions of the door at 36.

It might be said that the cross section of the edge of the door is that of one half of an ellipse cut diagonally. Mounted within the door to serve as a cushion for the lenses is a sheet 37 of paper board, cork, rubber or other resilient material and this sheet is made to fit within the largest diameter of the door, as shown in Fig. 2. This sheet is apertured as shown in Fig. 3 and when sprung into position prevents the lenses from falling out of the lamp door. It is held in position against the radial flange 16 of the shell and against the front edge 8 of the body by the pressure of the lenses and of the door through the action of the screws 40 which are described in my co-pending application.

In order to prevent the lens 25 from turning, which is desirable when the lens is corrugated in order to spread the rays of light laterally on the roadway as the vehicle on which the lamp is mounted is backing, a small metal clip may be attached to the upper portion of the packing 37. This clip preferably comprises a tongue 42 which extends into the notch 27 in the lens and two flanges 43 and 44 between which the packing

is gripped. Small teeth may be formed on these flanges 43 and 44 to firmly secure the clip in position on the packing.

I claim:

5. 1. In a signal lamp, the combination of a body having cylindrical ends, a circular lens, a lunate lens in the same plane therewith and having an edge fitting the edge of the first lens, a door to receive said lenses 10 and having a circumferential portion whose cross section is substantially one half of an ellipse cut diagonally, the inner edge of said portion engaging the lenses and the outer edge engaging the outer edge of the lamp 15 body, said door having a curved transverse portion extending over the adjacent edges of the two lenses, an apertured packing sheet fitting within the door and covering the edges of said lenses, and means to press the 20 door, lenses and packing toward the body.

2. In a lamp, the combination of a body,

a lens at one end thereof and having a notch in its edge, means to secure the lens to the body, a packing sheet between the lens and body, and a clip secured to the packing 25 sheet and extending into said notch in the lens to prevent the lens from rotating.

3. In a lamp, the combination of a body, 30 a lens at one end thereof, a door to secure the lens to the body and having an inturned edge, said body having an outer flange at an oblique angle to the adjacent wall of the body, the outer edge of the flange being bent outward toward the lens and parallel to the adjacent wall of the body and engaging the 35 inturned edge of the door, and an apertured sheet of resilient material between the edge of the lens and the body and contacting with the body at the inner edge of the flange thereon and with the outwardly bent edge 40 of said flange.

CHARLES E. GODLEY.
